UNITED STATES PATENT OFFICE

RUDOLF SCHNABEL, OF BERLIN, GERMANY, ASSIGNOR, BY MESNE ASSIGNMENTS, TO PYRENE-MINIMAX CORPORATION, A CORPORATION OF DELAWARE

PROCESS OF PRODUCING FOAM FROM FOAM GENERATING SUBSTANCES

No Drawing. Application filed April 23, 1927, Serial No. 186,165, and in Germany September 30, 1925.

My invention relates to a process of producing foam for extinguishing fires which have broken out in oil or gasoline tanks or the like and similar conflagrations which 5 cannot be extinguished by means of water.

The production of the foam according to my invention takes place by passing the liquid capable of developing foam, for instance a solution of saponin, together with 10 air or another gas under pressure through a turbine, the runner wheel of which is driven either by the foam developing liquid flowing in under pressure or by compressed air or another compressed gas. For the principle 15 of my invention it is immaterial whether a turbine with a blade wheel is employed or whether for obtaining the intended effect viz. the intimate mixture of the liquid with the gas, another device capable of being driven 20 by the pressure medium is employed, as for instance an apparatus operating on the principle of the reaction water wheel.

In practicing my invention the turbine or the like may be driven by a system of tangentially located nozzles by means of which alternately the liquid is introduced through one nozzle and compressed air or the like through the next. The arrangement could also be such that only one of the media serving 25 for the generation of the foam is introduced into the turbine under pressure, for instance the air or other gas and utilizing the mechanical energy of the turbine for supplying the other medium, for instance a solution of saponin, to the turbine.

Owing to the extraordinary high speed attainable in such a turbine an extremely intimate mixture of the two foam developing agents takes place, as extensive experiments 40 have shown, so that foam of any desired condition may easily be obtained.

It will be readily understood that the same or a similar effect may be attained by a turbine of the nature of a turbo-compressor operated by motor power or a turbine operating 45 in the manner of a siren.

Various changes and modifications may be made without departing from the spirit of 50 my invention and the scope of my claims

which should be read in the light of prior knowledge only.

I claim as my invention:

1. The process of producing foam from foam generating substances, which consists 55 in passing the foam generating liquid together with a gas under pressure through a turbine the runner wheel of which is driven by the liquid flowing in under pressure and the gas under pressure.

2. The process of producing foam from foam generating substances, which consists in employing one of the agents serving for the generation of the foam, either the liquid or the gas under pressure, for driving a turbine, utilizing the mechanical energy of said turbine for conveying and putting under pressure the other agent, and bringing the liquid and gas under pressure together to produce foam.

3. The process of producing foam from foam generating substances which consists in bringing together gas under pressure and a foam forming liquid under conditions such as to cause a combination of both in finely 75 divided condition through the driving of a mechanical mixing means by at least one of said substances.

4. The process of producing foam from foam generating substances which consists in 80 passing the foam generating substances including a foam generating liquid together with a gas under pressure through a turbine the rotor of which is driven by one of the substances flowing in under pressure.

In testimony whereof I affix my signature.

RUDOLF SCHNABEL.
